Hugh F. Ellard, Inventor.

UNITED STATES PATENT OFFICE.

HUGH F. ELLARD, OF MISSOULA, MONTANA.

FINGER-LINK.

1,244,303.

Specification of Letters Patent. Patented Oct. 23, 1917.

Application filed March 29, 1915. Serial No. 17,909.

To all whom it may concern:

Be it known that I, HUGH F. ELLARD, a citizen of the United States of America, residing at 542 South 3rd St. west, in the city of Missoula, in the county of Missoula and State of Montana, have invented a new and useful Finger-Link, of which the following is a specification.

My invention relates to improvements in finger-links, and the objects of my improvement are, first, to provide positive security in the operation of finger-links, and second, to afford facilities for easily and quickly detaching loads held by chains, ropes, cables, or otherwise, and fastened by or otherwise depending upon finger-links.

I attain these objects by the mechanism illustrated in the accompanying drawing in which—

20 Figure 1 is a composite view of the entire device. Fig. 2 is a top view of the link. Fig. 3 is a perspective view of the snap.

Similar letters apply to similar parts throughout the several views.

25 The link A constitutes the main framework and is to be attached to the end of a chain or cable B adapted to be attached to a load. The finger C passes through a ring or loop D with which it is desired to connect the chain, and is drawn back along side of the link A.

The ring E attached to the chains F and G and inclosing a section of the link A, is passed over the end of the finger C to hold it locked. To provide against accidental displacement of the ring it is held by chains F and G, snap H and link I. By releasing the snap H from link I, which latter is held by the loop in the end of link A, the ring 40 may be moved over the end of the finger C to release the latter.

I am aware that prior to my invention finger-links have been made without rings or links to hold the finger closed. I therefore do not claim patent rights on this broadly.

I claim as my invention:

1. In a finger link, a finger adapted to be shifted into operative position to hold a load, means for holding said finger in said operative position including a finger engaging element, a flexible member to which said element is secured, and means forming a continuation of said flexible member for preventing accidental displacement of said element.

2. In a finger link, a finger adapted to be shifted into operative position to hold a load, a ring adapted to be slipped over the end of said finger to hold it in such operative position, and flexible locking means secured to said ring.

3. In a finger link, a finger adapted to be shifted into operative position to hold a load, a locking ring adapted to engage said finger, a flexible support for said ring, and means secured to said support for preventing accidental displacement of said ring from said finger.

4. In a finger link, the combination with a main frame and a finger fulcrumed thereon, a link secured to said frame, a chain secured at one end to said frame, and a snap connecting the other end of said chain with said link, of a ring on said frame secured to said chain and adapted to engage said finger.

HUGH F. ELLARD.

Witnesses:

W. J. BABINGTON,
P. H. GERBER.
